BRANDING ATTACHMENT FOR
WRAPPING MACHINESJames E. McKinnon, Columbus, Ohio, assignor to
Mazer-Cressman Cigar Co. Inc., Detroit, Mich.

Application May 26, 1933. Serial No. 672,992

10 Claims. (Cl. 101—11)

This invention relates to branding attachments for wrapping machines, used for wrapping cigars in transparent tissue or the like.

For some years, especially since the wrapping of cigars in transparent tissue or the like has become a common practice, it has been considered desirable to brand the outer leaf of a cigar with a suitable legend, which may be the name of a large purchaser of cigars or which may be a trade name or trade mark. Prior to my invention, branding of cigars had been accomplished, but in a laborious and expensive fashion. In prior attempts at branding, completely manufactured cigars were transported to a branding station, where they were branded, and the branded cigars were then transported to a wrapping machine, which wrapped the branded and completely manufactured cigars. In known cases, the branding station included nothing more than a table and an automatically operable brander by means of which the brand was applied to the outer leaf of the cigar, the brander being of the heated roller type or of the heated press type.

Branding in this fashion, in a separate station, proved unsatisfactory for many reasons, a principal reason being the high percentage of cigars which were found to have broken outer leafs, and which had to be rejected. It, therefore, became an object of my invention to devise means for branding cigars in such a way that the percentage of broken-leaf cigars was effectively minimized.

In attaining my object, I sought the cause of broken leafs and discovered that branding by heat weakened the outer leaf to a considerable extent, especially immediately after branding, and that recently branded cigars could not withstand the abuse and abrasion incident to their being stacked in trays, as they left the branding station, and incident to their being transported, in stacks in trays, to the wrapping station. Following such discovery, I proposed to have the branded cigars carried individually to the wrapping devices, and further proposed to time the branding operation with respect to the wrapping operation in such a manner that there was no appreciable interval between the two operations.

In attaining my desires, I took cognizance of the fact that a common type of wrapping machine included an intermittently rotating table having pockets in which cigars were disposed, the machine carrying cigars, through various stations, to wrapping parts. I recognized that in this type of machine, one of the stations which preceded the wrapping station was an idle one and was not used for any purpose. I, therefore, proceeded to

utilize this station as a locus for a branding operation, and converted the station from an idle one into a branding station, by equipping the machine with a branding press, operating on cigars as they pass through this station. It then occurred to me to have the branding press automatically operable by a part which was synchronously timed to the intermittent rotation of the table. In the type of machine I had before me, I discovered a tripper arm disposed above the rotating table, which moved upwardly as the table rotated and moved downwardly when the table came to rest, in its intermittent rotation. I, therefore, proceeded to use this tripper part as the operating and timing means for the branding press and then proceeded to adapt a branding press for cooperating with this tripper part, for the purposes desired.

I first provided a horizontally disposed branding arm, positioned above the rotating table and pivotally mounted at one end thereof, on a horizontal pivot, to rotate in a vertical plane. The other end of the arm, namely, the free end, I connected to the tripper part, so that the branding arm would move up and down with the tripper part, the result being that the arm would move up before the table rotated out of its stations, and would move down when the table came to rest, in its intermittent rotation.

On the branding arm, I secured a vertically disposed branding iron having on its lower end a branding press, the latter being heated by the iron, and being carried by and with the arm in its intermittent up and down movement.

It then occurred to me to provide adjustable movement limiting or stop means for the branding arm so that the latter and its press would assume a predetermined and adjustably fixed position at the end of each downward or branding stroke of the same. This feature insured the branding press dropping down to and pressing against the cigar as much as necessary and no more, and prevented to a large extent, the branding of cigars too lightly or too heavily.

As a further safety feature, I provided, for the branding arm, a means for insuring the branding arm being raised out of branding position whenever the intermittent rotation of the rotating table was stopped by the operator, as for example, when he wished to shut down the machine for any reason whatever, it being observed that a recognizable distinction exists between the stopping of the rotating table in its intermittent station-to-station rotation, and an operator-con-

trolled, temporary or permanent stopping of the intermittent rotation of the table.

In the type of machine I had before me, I observed that the intermittent rotation of the table was stopped by the movement of a lever, manually controllable and operable by the operator. I, therefore, proceeded to create an operative connection between this lever and the branding arm of such a nature that whenever the lever was moved to discontinue the intermittent rotation of the rotating table, it automatically caused the branding arm to be elevated and maintained out of branding position. Accordingly, in the event that the intermittent rotation of the machine happened to be discontinued when a cigar was disposed in the branding station, as was usually the case, no damage would be done to that particular cigar by the prolonged application of the branding press to that particular cigar. Under such circumstances, the branding press was automatically elevated out of contact with the cigar by the very movement that discontinued the intermittent rotation of the table.

From the foregoing, then, it will be observed that there has been provided by the invention an efficient and satisfactory branding attachment for wrapping machines. One such attachment, in place on a wrapping machine, is disclosed in the appended drawings by way of illustration, and referring to these drawings, it will be seen that

Fig. 1 shows, in plan, parts of a common wrapping machine, equipped with a branding attachment of the invention and its accessories;

Figs. 2, 3, and 4, are elevational fragmentary sections as if on lines 2-2, 3-3, and 4-4, of Figs. 1, 1, and 2, respectively;

Fig. 2 showing the branding arm, together with its associated parts;

Fig. 3 showing the means for discontinuing intermittent rotation of the rotating-table, and for automatically and simultaneously elevating the branding arm, when the intermittent rotation of the rotating table is discontinued; and

Fig. 4 showing, in elevation, the connection between the tripper part of the machine and a part of the branding arm;

Fig. 5 shows, in up-side-down perspective view, the branding press fabricated to brand the fictitious word, "Xmith" on the outer leaf of a cigar.

For an understanding of the drawings, reference is had to the following detailed description of the parts therein shown, in which description reference numerals are used to denote correspondingly numbered parts of the drawing, like figures being chosen for like parts.

In the drawings, there is shown parts of a common type of wrapping machine, one which includes a stationary top or table 10 above which intermittently rotates a horizontally disposed cigar carrying table 11, the latter being supported on a vertical pedestal 12, and being actuated by a suitable intermittent rotation mechanism, such as a Geneva mechanism or the like, the same not being shown since it forms no part of the present invention. The rotating table is provided with a plurality of elongated pockets 14 disposed in a more or less circular arrangement around the table, the pockets opening upwardly and being shaped and proportioned to receive and hold in place cigars to be branded and wrapped.

In the machine shown, there happen to be six pockets 14 and consequently six stations, sta-

tions 1 to 4 only being specifically indicated by numerals, and these stations will briefly be described as follows: In station 1, a cigar 16 is introduced into the pocket 14, the cigar occupying a position in the pocket substantially as shown. As the table 11 rotates counterclockwise, the cigar is moved from station 1 to station 2, and since this station is the branding station, the top surface of the cigar, in this station, will be branded by the branding attachment which will later be described. From the branding station, the cigar is moved through station 3, which is an idle station, to station 4, where it is wrapped by means of a wrapping device, not here shown, since it forms no part of the present invention.

Disposed above the table 11 and crossing it, is a tripper bar 20, connected to a tripper shaft 22, and to the table rotating means in such a manner that it moves in a vertical plane and about the axis of the rod 22 as a pivot, upwardly before each station-to-station rotation of the table 11, and downwardly whenever the table comes to rest in a station. It happens that the tripper part has a definite and useful purpose in the machine as it is originally constructed, prior to my alteration of the same and without interfering with this purpose, I use the tripper part as an actuating and timing means for the branding attachment, as will be described in a later stage of the specification.

For starting and stopping the intermittent rotation of the table 11, there is provided a control lever 24 latched by means of a conventional rack and plunger arrangement 26, and connected by a shaft 28 to the table rotating mechanism.

The parts heretofore described are all part of the machine as it was before I effected the alterations and applied the attachments which permit the carrying out of a branding operation at station 2, and accordingly form no part of my invention except insofar as they cooperate with the branding attachments whose parts are now to be described.

The branding attachment includes an elongated, horizontally disposed, branding arm 30 pivotally mounted on and connected at one end to a pedestal 32 projecting upwardly from the stationary table 10, the pivot being in the nature of a removable pin 34 having an enlarged handle end 36 and held by a cotter pin 38. The branding arm 30 passes above the rotating table 10 and by station 2, and a portion thereof near such station is provided with a horizontal hole through which passes the bolt end 40 of a clamp member 42, this clamp member being held to the branding arm by a nut 44 threaded on the bolt end 40, there being a boss or a second nut 46 formed on the bolt 40 for assisting in securing the clamp part 42 with respect to the arm 30. A second clamp part 48 connected to the first by bolts 50 passing through ears 52 formed on the ends of the clamp parts 42-48, cooperates with the clamp part 42 to clamp in place a branding iron which is in the nature of an elongated metal cylinder 54 containing an electrically heating element or coil, not shown, the upper end of the cylinder 54 being provided with a wooden or heat insulating handle 56 through which passes the cord 58 which conducts electrical current to the heating element in the cylinder 54, the cord having on its free end a conventional plug 60 for connection to an electrical circuit. The lower end of the cylinder is provided with a conical chuck 62 into whose bore may be passed a post 64 formed as part of the branding press 66, the post 64

being clamped in place in the chuck by a set screw 68.

The branding press 66, shown best in Figs. 2 and 5, in the forms illustrated, includes a base plate 70, generally of L cross section and adapted to seat a clamping bar 72 which may be held to the base plate 70 by means such as screws 74, the parts cooperating to define a slot 76 for the reception of the branding indicia. These may be formed as raised letters on small blocks 78 disposed in the slot 76 and held against movement by small clamping blocks 80, in turn held in place by means such as screws 82, all as indicated in Fig. 5. The indicia, in this case the letters "Xmith" project a slight degree beyond the level or flush surface of the parts 70, 72, of the branding press, so that when the press is moved down, only the indicia will engage the top surface of the cigar 16 disposed in the pocket 14 that happens to be in station 2.

The free end of the branding arm 30 is provided with a blade like part 90 which passes through a U-shaped strip or bail 92 secured to the tripping part 20 by means such as screws 94, the clearance between the blade 90 and the slot 96 in the U-shaped strip 92 being such that no binding interference between the blade and the tripper part 20 will take place, when they move together and relatively.

The operation of the machine, as equipped with the novel branding attachment, is as follows: When the table 11 rotates intermittently, and just before it moves out of its stations, the tripping part 20 will move vertically, rising just before the table rotation and dropping as the table comes to rest. When the tripping part 20 moves upwardly, it lifts the branding arm 30 and the press 66 carried thereby, and consequently the press will clear the table 11, and the cigars in pockets 14. When the table comes to rest, the tripping part 20 will drop, and will permit the branding arm 30 and the press carried thereby to drop so that the indicia will engage the top surface of the cigar 16 that happens to be in station 2.

In order to prevent the indicia from branding the cigar too lightly, the parts are so connected that the arm 30 will tend to drop considerably below its desired position, this insuring the indicia engaging the cigar, heavily enough at least. However, to prevent too heavy a contact or engagement, there is provided a stop or movement limiting means which is in the nature of a bolt 110 projecting upwardly from the stationary table 10, under and in the path of movement of the arm 30, the upper or headed end of the bolt acting as a stop for the arm 30. A check nut 102, threaded on the bolt 100, securely locks the bolt in a predetermined desired position, the bolt being adjustable to vary the amount of drop of the arm 30.

In order to prevent the attachment from being caused to come to rest, for a long interval, in engagement with a cigar that happens to be in station 2, and consequently burning the cigar so positioned, the shaft 28 which starts and stops the intermittent rotary movement of the table 11 is provided with a crank 110 connected by a pin in the form of a bolt 112, to a vertical rod 114, slideable through a hole 116 in the stationary table 10, this rod being in the path of movement of and under the arm 30 and having a hardened upper end. It will be seen that when the lever 24 is moved counterclockwise, Fig. 3, to discontinue rotation of the table 11, pin 114 is caused to move upwardly to engage arm 30

and lift it a considerable distance, enough so that the branding press will clear the cigar that happens to be positioned in station 2, even though the tripper part 20 is down.

In the foregoing, there has been described an embodiment of the invention which was created to conform to the particular machine I had before me. I do not wish, however, to have my invention limited to the particular machine I have illustrated, for it is obvious that similar but somewhat different wrapping machines may be equipped with the branding attachment of the invention without departing from the spirit of the invention, modifications being effected as desired and as will be well within the purview of the ordinary skilled mechanic.

Now having described the illustrated embodiment, reference will be had to the appended claims which will determine the scope of the invention.

1. In a machine for wrapping cigars, means for moving a cigar through a plurality of stations, intermittently and with rest intervals, one of said stations being a loading station, a succeeding station being a branding station, and a still later station being a wrapping station, a heated press for branding a cigar while it is in the branding station, means synchronously timed to the intermittent motion of the cigar moving means for moving said press into engagement with a cigar after the latter comes to rest in the branding station, and for moving said press out of engagement with the cigar before the latter is moved out of the branding station, and means for automatically moving the press out of branding position when the intermittent motion of the cigar moving means is discontinued.

2. In a machine for wrapping cigars, means for moving a cigar through a plurality of stations, intermittently and with rest intervals, one of said stations being a loading station, a succeeding station being a branding station, and a still later station being a wrapping station, a heated press for branding a cigar while it is in the branding station, means synchronously timed to the intermittent motion of the cigar moving means for moving said press into engagement with a cigar after the latter comes to rest in the branding station, and for moving said press out of engagement with the cigar before the latter is moved out of the branding station, and means for automatically moving the press out of branding position when the intermittent motion of the cigar moving means is discontinued, the last mentioned means being connected to and operated by the means for discontinuing intermittent motion of said cigar moving means.

3. In a machine for wrapping cigars, heated press for branding the outer leaf of a cigar, means for transporting a branded cigar, individually, and without its being caused to come in abrasive contact with other cigars, to a wrapping means, and means for wrapping a branded cigar, the last mentioned means operating on a cigar immediately after it has been branded, and means synchronously timed to the motion of the cigar transporting means for moving said press into engagement with a cigar when the latter is at rest in a branding station and for moving said press out of engagement with the cigar while the latter is still at rest in the branding station, and means for automatically moving the press out of branding position when the transporting means is rendered inoperative.

4. In a machine for wrapping cigars, heated

- press for branding the outer leaf of a cigar, means for transporting a branded cigar, individually, and without its being caused to come in abrasive contact with other cigars, to a wrapping means, and means for wrapping a branded cigar, the last mentioned means operating on a cigar immediately after it has been branded, and means synchronously timed to the motion of the cigar transporting means for moving said press into engagement with a cigar when the latter is at rest in a branding station and for moving said press out of engagement with the cigar while the latter is still at rest in the branding station, and means for automatically moving said press out of branding position when the transporting means is rendered inoperative, the last mentioned means being connected to and operated by the means for rendering the transporting means inoperative. 80
- 10 5. In a multi-station unitary machine for branding and wrapping cigars, a rotatable carrier having individual cigar receiving pockets, branding means in one station operating on a cigar in a pocket at that station, and wrapping means in a succeeding station operating on a recently branded cigar in a pocket at that station, each branded cigar, en route to the wrapping means, being transported individually while remaining in its pocket and out of abrasive contact with other cigars. 85
- 15 6. In a multi-station unitary machine for branding and wrapping cigars, a rotatable carrier having individual cigar receiving pockets, heated press branding means in one station operating on a cigar in a pocket at that station, and wrapping means in a succeeding station operating on a recently branded cigar in a pocket at that station, each branded cigar, en route to the wrapping means, being transported individually while remaining in its pocket and out of abrasive contact with other cigars. 90
- 20 7. A machine of the character described in claim 5 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station. 95
- 25 8. A machine of the character described in claim 5 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 100
- 30 9. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station. 105
- 35 10. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 110
- 40 11. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 115
- 45 12. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 120
- 50 13. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 125
- 55 14. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 130
- 60 15. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 135
- 65 16. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 140
- 70 17. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 145
- 75 18. A machine of the character described in claim 6 including means for intermittently moving the rotatable carrier, means synchronously timed to the intermittent motion of the carrier for moving the branding means into engagement with a cigar after the latter comes to rest in a branding station, and for moving the branding means out of engagement with a cigar before the latter is moved out of the branding station, and means for automatically moving the branding means out of branding position when the intermittent motion of the carrier is discontinued. 150
